ATTORNEY

UNITED STATES PATENT OFFICE.

GEORGE R. COOK, OF PORTLAND, OREGON, ASSIGNOR OF ONE-HALF TO ALBERT HOAG,
OF PORTLAND, OREGON.

BROOM.

1,372,654.

Specification of Letters Patent. Patented Mar. 22, 1921.

Application filed January 19, 1920. Serial No. 352,643.

To all whom it may concern:

Be it known that I, GEORGE R. COOK, a citizen of the United States, and a resident of Portland, county of Multnomah, State 5 of Oregon, have invented certain new and useful improvements in Brooms, of which the following is a specification.

My invention relates to brooms in general, and particularly to the ordinary type of 10 household broom used by domestics, the object of my invention being to provide in a substantial construction means of using fiber bristles in the place of the usual corn bristles, and to provide said means of cheap 15 manufacture obviating all necessity of passing the bristles through holes or otherwise stringing them through any member of the broom.

I accomplish the above object, and other 20 desirable results that will hereinafter appear, by means of the construction illustrated in the accompanying drawing, which is a part of this application for letters patent, like characters of reference indicating like parts throughout the several views 25 thereof, and in which:

Figure 1 is a side elevation of a broom embodying my invention.

Fig. 2 is an edge elevation of the lower 30 portion of the broom upon an enlarged scale, parts being broken away.

Fig. 3 is a side elevation of the lower portion of the broom, parts being broken away.

Fig. 4 is a perspective view of the block.

Fig. 5 is a perspective view of the collar.

Fig. 6 is a perspective view of the lower end of the handle.

In general my invention consists of a plurality of bundles or bunches of coarse fiber 40 bristles secured to the lower edge of a suitably shaped block, a collar surrounding said bundles of coarse fibers, an outer layer or envelop of fine fibers entirely surrounding 45 said coarse fibers and said block, a handle secured to said block, and a flexible envelop encompassing the top of said block and the bottom of said handle.

The block 7 is provided with a straight 50 lower edge 7^a upon which the several bundles of coarse fibers 8 are secured, and a curved upper edge 7^b which portion is notched as at 9 to receive the lower end of the handle 10, said lower end of the handle being squared to fit said notch, and hav-

ing thereon a dowel 11 adapted to enter an orifice 12 in said block.

The handle is secured in said notch 9 by means of strips 13 and 14 nailed to the block 7 and crossing the notch 9 therein, as shown 60 in Figs. 2 and 3, and also by nails 15 through the upper edge of the block 7.

The coarse fibers, composing the central portion of the broom bristles, are assembled 65 in bundles of suitable size, and bent over in the middle until the opposite ends of the bundle become adjacent, in which condition they are secured in place upon the lower edge 7^a of block 7 by wires 16. The wire is fastened upon one side of the block 70 7 adjacent the edge 7^a thereof, and then passed through the loop at the middle of one of the bundles of coarse fibers 8 and around said edge 7^a of the block to a nail 7 upon the opposite face of the block 7 75 to that upon which the wire was first fastened. The wire is then passed from nail 17 to an adjacent nail 18 and thence through the loop in another bundle of coarse fibers 8 and around the edge 7^a of the block to a nail 80 upon the opposite side thereof. This process is continued until as many bundles of coarse fibers 8 as desired are secured to the block 7, as shown in Figs. 2 and 3, the wire being drawn tight as each bundle is 85 placed in position.

When the last bundle has been placed in position and the end of the wire 16 has been fastened by a nail, a collar 19 is placed in position around the upper end of the block 90 7, as shown in dotted lines at 19^a in Fig. 3, and is slipped down until it is in position at the lower edges of the block 7, slightly overlapping the same and embracing both the lower portion of said block and 95 the upper portions of the bundles of coarse fibers 8, as shown in Figs. 2 and 3. When in this position said collar 19 is fastened to said block 7 by nails 20, and nails or pieces of wire 21 are passed through said 100 collar from side to side thereof between adjacent bundles of coarse fibers 8 and clenched in position, thereby firmly binding all said bundles into said collar.

When the bundles of coarse fibers 8, the 105 collar 19 and the handle 10 have all been placed in position and secured therein, as above explained, the greater portion of the block 7 and all of the bundles of coarse fibers 8 are surrounded or incased within an envelop 110

of fine fibers 22, said fine fibers beginning at a point adjacent the upper portion of said block 7 and extending downward to the lower extremities of the coarse fibers 8, and 5 being secured upon said block 7 by numerous wire bands 23 stapled to the block 7, and by a flat band 24 surrounding said fine fibers 22 at a point adjacent the lower edge of said collar 19, which band 24 is secured in place 10 by nails or wires 25 passing through the same from side to side and also through the collar 19, and being clenched in position.

A cloth shroud 26 is inserted beneath the upper of wires 23 and is then turned upward 15 and gathered around the lower end of the handle 27 and secured thereon by a thimble 28 thus providing a neat finish for the broom.

It will be observed that this construction 20 is very substantial because the coarse fibers are bound upon the block in a very secure manner and are also held together by the collar 19; that it is economical in construction because it avoids all threading of fibers through holes, and also because it uses a 25 shorter length of fine fibers than is required when said fine fibers are gathered around the lower end of the handle as is the usual practice; and that the final appearance of the broom is neat and attractive.

30 My device may be made of any size and constructed of any materials deemed convenient and suitable for a device of this character, and while I have illustrated and described a form of construction and arrangement of parts found desirable in materializing my invention, I wish to include 35 in this application for Letters Patent all

mechanical equivalents and substitutes that may fairly be considered to come within the scope and purview of my invention as defined in the appended claims. 40

Having disclosed my invention so that others may be enabled to construct and to use the same, what I claim as new and desire to secure by Letters Patent is: 45

1. In a broom, a block; a handle secured to said block; a plurality of bundles of bristles bent double at the center thereof and secured upon one edge of said block by a wire, said wire being passed from side to 50 side of said block thereby forming a plurality of loops in each of which loops one of said bundles is secured, said wire being fastened to said block intermediate each of said loops; and a collar surrounding the 55 lower edge of said block and extending downward over said bundles.

2. In a broom, a plurality of bundles of fibers secured upon the edge of a block by a wire attached to said block and forming 60 a plurality of loops around the edge thereof, each of said loops embracing one of said bundles of fibers; and a collar encircling the edge of said block and the upper ends of 65 said bundles of fibers.

In witness whereof I claim the foregoing as my own I hereunto affix my signature in the presence of two witnesses, at Portland, county of Multnomah, State of Oregon, this 30 day of Dec., 1919.

GEORGE R. COOK.

Witnesses:
